DESIGN FOR A REAR FRAME MEMBER FOR A VELOCIPED

Bert J. Anderson, Hammond, Ind.

Application April 23, 1937, Serial No. 68,953

Term of patent 14 years

To all whom it may concern:

Be it known that I, Bert J. Anderson, a citizen of the United States, residing at Hammond, in the county of Lake and State of Indiana, have invented a new, original, and ornamental Design for a Rear Frame Member for a Velocipede, of which the following is a specification, reference being had to the accompanying drawing, forming part thereof.

The figure is a perspective view of a rear frame member for a velocipede showing my new design.

I claim:

The ornamental design for a rear frame member for a velocipede, as shown.

BERT J. ANDERSON.
